CLAIM

The ornamental design for a rack for fiberoptic scopes or the like, as shown and described.

DESCRIPTION

FIG. 1 is a top elevational view of the rack for fiberoptic scopes or the like showing my new design;
FIG. 2 is a front elevational view thereof, and
FIG. 3 is an end elevation thereof.

The rear of the rack for fiberoptic scopes or the like is flat and unornamented.

FIG. 1

FIG. 2

FIG. 3
